DESIGN FOR A DISPLAY DEVICE

Edward H. Torbeck and Warren Dunn, Altamont,
Ill.; said Dunn assignor to said Torbeck

Application April 21, 1941, Serial No. 100,545

Term of patent 14 years

To all whom it may concern:

Be it known that we, Edward H. Torbeck and Warren Dunn, citizens of the United States of America, residing at Altamont, in the county of Effingham, State of Illinois, have invented a new, original, and ornamental Design for Display Devices, of which the following is a specification, reference being had to the accompanying drawing, forming a part thereof.

Fig. 1 is a side view of a display device, show-

ing our new design, with a portion of the base thereof cut away through A—A of Fig. 2.

Fig. 2 is a top view of the display device of Fig. 1, drawn upon a reduced scale for convenience in illustration.

We claim:

The ornamental design for a display device, as shown.

EDWARD H. TORBECK.
WARREN DUNN.
